ATTORNEYS.

UNITED STATES PATENT OFFICE.

LENA LUFTIG, OF NEW YORK, N. Y.

SLEEVE CUFF.

Application filed March 20, 1922. Serial No. 545,108.

To all whom it may concern:

Be it known that I, LENA LUFTIG, a citizen of the United States, and resident of New York, in the county of Bronx and State 5 of New York, have invented certain new and useful Improvements in Sleeve Cuffs, of which the following is a specification.

It has been found that duck coats such as are commonly worn by barbers, waiters, etc. 10 after a comparatively short amount of wear, break and crack about the edges of the cuff sleeves, and while the remaining parts of the garment are in practically perfect condition, the coat must either be discarded altogether or furnished with entirely new 15 sleeves or cuffs. This breaking or cracking of the material is due to various causes, one being the characteristic stiffness of the material, another being due to the severe 20 methods of laundering, starching and machine ironing usually employed, and another being due to the fact that in order to obtain the proper form and set to the cuffs it is 25 impossible to turn back the material to form a double thickness for the cuff because of the taper of the sleeves, consequently the double 30 thickness of the cuff is made by sewing on a separate piece of material and the wearing or outer edge of the cuff must therefore in 35 order to avoid raw or cut edges be formed by turning in a hem on each of the plies of the cuff, thereby producing four thicknesses of material at the cuff edge. Due to the 40 strong washing and bleaching solutions used 45 in the laundering of garments of this type, these four thicknesses of material absorb and retain more of the solutions than the remaining parts of the garment and which consequently causes the rapid destruction of 50 the wearing edge of the cuff and the cracking or breaking thereof heretofore referred to.

One of the principal and more specific objects of this invention is therefore to provide 45 a new and improved construction of a sleeve cuff which will obviate the difficulties hereinbefore set forth and will consequently prolong the life of a garment of this type.

Another object is to provide a novel construction of a sleeve cuff by means of which an insertion piece of like or of softer and more pliable material than the garment is placed upon the outer edge of the cuff.

A further object is to provide a novel construction by means of which this insertion

piece may be readily removed and a new piece quickly and easily inserted if it should become necessary or desirable.

A further object is to provide a reinforcing strip for a sleeve cuff which will not detract from the appearance of the garment. 60

Considered in its broader aspects, this invention relates to an improved construction of a sleeve cuff applicable to all types of garments as well as to those heretofore set 65 forth and has for one of its objects the provision of a simple construction for reinforcing a sleeve cuff which can be embodied in the garment during the manufacture thereof at a very slight additional cost. 70

For the accomplishment of these and such further objects as will hereinafter be apparent to those skilled in the art to which this appertains, the invention consists in the construction, combination and arrangement 75 of parts herein specifically described and illustrated in the accompanying drawings, wherein is shown a preferred embodiment of the invention, but it is to be understood that changes, variations and modifications may 80 be resorted to which fall within the scope of the claims hereunto appended.

In the drawings forming a portion of this specification.

Fig. 1 is a perspective view of a sleeve 85 cuff embodying my invention.

Fig. 2 is a cross sectional view on the line 2—2 of Fig. 1.

As shown in the drawings, the sleeve 10 is provided with the usual cuff 11 formed of two plies of material 12, 13 which are stitched together as at 14 a short distance from the outer edge of the cuff. An insertion piece 15 of the same or of a softer and more pliable fabric than the material of the 90 garment is folded upon itself and the folds stitched together as at 16. The insertion piece is then inserted between the outer free edges of the cuff beyond the stitching 14 and a final row of stitching 17 is then run 95 through both plies 12 and 13 and the insertion piece 15. 100

The insertion piece 15 being of less thickness than the usual four plies is therefore 105 softer and will not crack or break as readily as the cuff edge as usually constructed. By means of such construction, when the insertion wears out, the face ends of the cuff members may be opened by removing the stitching 17, and a new insertion applied to 110

the cuff layers, or the cuff layers may be stitched together without the use of any insertion if so desired.

Having thus described my invention, what I claim as new and desire to secure by Letters Patent of the United States, is:

1. A sleeve cuff formed of a plurality of layers of material having their free ends doubled over inwardly on themselves, said layers being stitched together near their free ends on a line spaced from the outer margin of said turned over free ends, and an insertion formed of a piece of fabric doubled over on itself and stitched to the overlapping free ends of said cuff at the outer margin of said cuff layers.
2. A sleeve cuff formed of a plurality of layers of material having their free ends doubled over inwardly on themselves, said layers being stitched together near their free ends on a line spaced from the outer margin of said turned over free ends, and an insertion formed of a piece of fabric doubled over on itself, and stitched to the overlapping free ends of said cuff at the outer margin of said cuff layers, and also stitched together independently of said cuff layers.

Signed at New York in the county of New York and State of New York this 10th day of March A. D. 1922.

LENA LUFTIG.
